D. S. FISHER, OF CEDAR SPRING, INDIANA.

Letters Patent No. 65,195, dated May 28, 1867.

WHEAT-DRILL.

The Schedule referred to in these Letters Patent and making part of the same.

TO ALL WHOM IT MAY CONCERN:

Be it known that I, D. S. FISHER, of Cedar Spring, in the county of Harrison, and State of Indiana, have invented a new and improved Wheat-Drill; and I do hereby declare that the following is a full, clear, and exact description thereof, which will enable others skilled in the art to make and use the same, reference being had to the accompanying drawings forming part of this specification.

This invention relates to a new and improved drill for drilling in wheat and other grain.

The invention consists in the employment or use of a rotary shaft provided with pins, in connection with a reciprocating seed-distributing slide; all arranged to operate in the manner substantially as hereinafter fully shown and described. In the accompanying sheet of drawings—

Figure 1 is a side sectional view of my invention, taken in the line *z z*, fig. 2.

Figure 2, a plan or top view of the same.

Similar letters of reference indicate like parts.

The parts comprising my invention are shown in black, and it is bolted to a frame mounted on wheels, and which is shown in red outline.

A is a seed-box of oblong form, which is bolted on the frame shown in red in a transverse position. This box A has a shaft, B, fitted longitudinally within it, said shaft having pins *a* radially attached, and rotated by means of a chain or belt from the axle of the front wheel of the frame on which the seed-box is secured, as shown in red in fig. 2. This chain or belt passes around a pulley, C, on the shaft B, said pulley being enclosed between two partitions, *b b*, as shown in fig. 2. In the lower part of the box A there is placed a perforated board, C', the perforations being of funnel form as shown at *c' c'* in fig. 1, and underneath this board C' there is placed a reciprocating slide, D, provided with openings *d*, as also shown in fig. 1. The bottom of the box A is also perforated with holes *e*, and an elastic tube, *f*, is secured over each hole, said tubes *f* being fitted in metallic tubes *E* which have arms *g* extending from their rear sides. The arms *g* are pivoted between pendent ears *h*, attached to the under side of the seed-box, and the rear end of each arm is pivoted to a vertical bar, F. These bars F extend up through guides *h' h'*, attached to the rear side of the box A, the bars being perforated to receive wooden pins *i* underneath the guides. These pins *i* keep the tubes *E* in proper working position, and in the event of a tube coming in contact with any obstruction, the wooden pins *i*, which hold it, will break and allow the tube to be forced back so that it may clear the obstruction. The slide D extends through one end of the box A, and has an arm, *j*, projecting from it at right angles, said arm having a rod, G, attached which passes along in front of the box A, and has a notch, *k*, made in it for a cam, H, to work in. This cam H is formed of a wheel, the axis of which is in a frame, I, attached to the front of the box A, said wheel having bevelled projections *r* at each side of it to act against the sides of the notch *k*, the projections at one side of the wheel being in line with the spaces between the projections at the opposite side, as shown in fig. 2. By this means a positive reciprocating movement is given the slide D, springs being avoided, and the seed discharged from the box A into the tube E. The rotating shaft B, with its pins *a*, prevents the seed from clogging or choking in the box A.

Having thus described my invention, I claim as new, and desire to secure by Letters Patent—

The rotating shaft B, provided with the pins *a*, in combination with the perforated board C, and the reciprocating slide D, operated by the cam H, all arranged substantially in the manner as and for the purpose set forth.

D. S. FISHER.
